CATHODE-RAY TUBE GUNSIGHT

Phillip Rood Wheeler, Alexandria, Va.

Application December 19, 1945, Serial No. 636,047

2 Claims. (Cl. 88—1)

(Granted under the act of March 3, 1883, as
amended April 30, 1928; 370 O. G. 757)

1

The present invention relates to gun sights and particularly to electrical gun sights operating on the disturbed-line-of-sight principle. In accordance with my invention I provided in a gun sight of the type in which a line of sight is established by aligning a reference image and a viewed target a novel combination of cathode ray tube means for producing an electrically displaceable reference mark and means normally stationary relative to the tube means for reflecting the mark into the field of view of an operator. The present application is a continuation-in-part of my co-pending United States patent application Serial No. 510,403, entitled "Cathode ray gun sight," and filed in the United States Patent Office on November 15, 1943, now abandoned.

I am aware that the prior art embraces several electrical gun sights which are premised on the disturbed-line-of-sight principle and which utilize one or more electrical indicating instruments for positioning cross hairs in elevation and in azimuth. The intersection of the cross hairs constitutes a sighting reference mark. In firing a gun at a moving target it is necessary to establish a line of sight on the target and so to establish the line of fire that it leads the line of sight by an amount functionally related to target speed and range. This "leading" is accomplished by the "target velocity" corrections of the sight setting. In the absence of these corrections the projectile would pass behind the target.

The corrections to the sight settings in the prior art are made in various ways. The cross-hairs in the sight are connected in some cases to electric meters whose fluctuations are the function of the rate of movement of the gun mount. Other sights have moveable reticles connected mechanically to the gun mount by gearing or cables, or have tiltable mirrors so connected and positioned in the focusing section of the sight so as to cause the reticle to move as desired. In each of these, the members of the sight forming the displaceable reference mark have mass and inertia, and are subject to mechanical lag in operation or overcontrol due to inertia. Such sighting devices of the prior art are inaccurate in operation as a result of the above mentioned defects.

My invention avoids the above mentioned disadvantages and limitations of the prior art by providing cathode ray tube means for producing an electrically displaceable reference mark and means normally stationary with respect to the tube means for reflecting the mark into the field of view of the gun-sight operator. My invention resides in the providing of the cathode ray tube

2

means for producing the reference mark and in the combination of that means with the reflecting means. My invention offers a further advantage in that sights in accordance therewith do not require additional arrangements for illuminating the reticle or reference image.

An object of this invention, accordingly, is to avoid the disadvantages and limitations dependent upon the use of prior art gun sights by employing a cathode ray tube to transmit the sight corrections to the gunner.

A further object of this invention is to provide a novel gun sight in which a combination of a cathode ray tube and reflecting means is employed to provide an electrically displaceable reference image for the gunner.

Still a further object of the invention is to provide a cathode ray tube gun sight which acts instantaneously and without any substantial loss of time due to transmission or damping of moving elements, or which may be damped electrically by a desired amount.

For a better understanding of the present invention together with other and further objects thereof reference is made to the following specification, to the claims appended thereto and to the accompanying drawings in which:

Fig. 1 comprises a geometrical presentation of the target velocity portion of the fire control problem;

Fig. 2 comprises a geometrical presentation of the superelevation portion of the fire control problem;

Fig. 3 is a perspective view of operative portions of an antiaircraft machine gun and mount showing the cathode ray tube gun sight installed thereon;

Fig. 4 is a view similar to Fig. 3 and showing a gunner using the cathode ray tube sight;

Fig. 5 is a vertical sectional view of my improved cathode ray tube gun sight;

Fig. 6 is a cross-sectional view of another form of my novel cathode ray tube gun sight;

Fig. 7 is a view looking toward the muzzle of a machine gun, showing the cathode ray tube sight in position thereon and also showing the rate generators;

Fig. 8 is a side view of the cathode ray tube gun sight mounted on a machine gun;

Fig. 9 is a complete wiring diagram for coupling the rate generators and the superelevation control potentiometer, through amplifiers, to the beam-deflecting plates of the cathode ray tube; and

Fig. 10 is a schematic diagram, partly in block

form, showing a similar circuit arrangement for producing and deflecting a circular reference image.

Fig. 1 shows the essential features of the short range antiaircraft fire control prob'em. A gun 11 is fired at an airplane target 12. At the instant of fire the airplane is on a position called the "present position." The gun should be pointed at some later position of the target, called the "future position," such that the projectile will reach the future position at the same time as the target. The angle between the line from the gun to the present target position (or line of sight) and the line from the gun to the future position (or line of fire) is the lead angle. This lead angle has components in elevation and in azimuth. One of the parameters upon which the proper lead angle and sight setting are premised is the component of target velocity in the plane of elevation. Another is the component of target velocity in the azimuthal plane.

The angular velocity of the target as observed from a gun on a stationary platform is the angular movement of the target about the gun per second of time. The time of flight is obviously the time taken by a projectile to reach the target. The total angular motion of the target during the time of flight is approximately equal to the angular velocity of the target at the present position multiplied by the time of flight in seconds. Other quantities involved in the lead-computing fire control problem, such as present and future slant range are approximately labeled in Fig. 1. It will be seen that range or time of flight is a parameter in part determinative of the appropriate lead angle.

If the gun barrel is pointed at the future position of the target without further correction the projectile would then fall below the target because of the downward force of gravity. To compensate for this undesired effect of gravity the gun elevation is increased by an additional angle herein called the "superelevation angle," as illustrated in Fig. 2. The superelevation angle required is dependent upon. (a) the ballistics of the gun and projectile, (b) the time of flight of the projectile to the target, (c) the cosine of the angle of gun elevation. The ballistics for a given gun can be considered constant over short ranges and therefore the superelevation angle is calculated with a reasonable approximation according to the following equation:

$$\text{Superelevation} = \text{constant } X \text{ time of flight } X \text{ cosine of gun elevation.}$$

In gun sights which operate on the disturbed-line-of-sight principle the gunner maintains the line of sight on a target by tracking the target and as he does so he manually positions the gun and the sight housing. The required target velocity and superelevation corrections furnish a basis for angularly so disturbing the line of sight with respect to the line of fire that when the line of sight is maintained on the target, the line of fire is appropriate to cause a hit to be scored.

In my above-mentioned copending patent application Serial No. 510,403, there is illustrated a complete cathode ray tube gun sight in which an electrically displaceable reference mark provided by a cathode ray tube is reflected into the field of view of a gunner. By aligning the optical image of that reference mark with a target the gunner establishes a line of sight. The cathode ray tube beam, and therefore the mark, are deflected in accordance with the movements of the gun in

elevation and in train relative to axes on a supporting frame in order to disturb the line of sight with respect to the line of fire by an amount appropriate to introduce the correction for target velocity. In my copending patent application Serial No. 636,045, entitled "Gun sight superelevation control device," filed in the United States Patent Office on December 19, 1945, there is shown a gun sight of the type in which a reference mark is electrically deflected, not only for the purpose of introducing the target velocity corrections, but also for the purpose of introducing the superelevation correction and thus overcoming the undesired effects of gravity. In my copending patent application Serial No. 636,048, entitled "Gyroscopically controlled electrical gun sight," filed in the United States Patent Office on December 19, 1945 there is shown a system which provides for the introduction of electrical corrections to compensate for both roll and pitch of the supporting plane on which the gun and sight are supported. In my copending patent application Serial No. 636,046, entitled "Electrical gun sight superelevation and roll correcting device," filed in the United States Patent Office on December 19, 1945, there is disclosed an arrangement for introducing both roll and superelevation corrections. The claims in the instant case are addressed to a combination which may be employed in any one of the sights disclosed in those copending patent applications. For purposes of clarity of description my invention is herein embodied in a gun sight which furnishes corrections for target velocity, range (or time of flight) and superelevation only. In the following description it may be assumed that the gun mount is supported on a stable horizontal plane.

Referring now generally to Figs. 3, 4, 5, 6, 9 and 10 there is illustrated, in an automatic compensating gun sighting arrangement, a gun mount generally indicated by the numeral 13, a gun 14 mounted thereon to permit both vertical and horizontal rotative movement of the gun, and a gun sight generally indicated by the numeral 15. This gun sight comprises the following:

Cathode ray tube means 17 for providing a sighting reference mark, beam-deflecting means 95, 96, 106 and 107 (Fig. 9) for positioning the reference mark, means 39, 44 actuated by rotative movements of the gun for controlling the positioning means, thereby to deflect the reference mark in such ratio to the gun motion as to cause the line of fire to lead a moving target 12 by an amount which compensates for the speed of the target, and means generally indicated by the numeral 18 and governed by the elevational position of the gun for further controlling the positioning means, thereby to move the reference mark in such manner as to cause the line of fire 19 to be elevated with respect to target 12 by an amount which compensates for the effect of gravity on a missile fired from the gun. There are also disclosed means 73, 74, 73', 74', 65 (Fig. 9) for so controlling the positioning means that the angular relationship between the line of sight and the line of fire is also functionally related to the range of the selected target 12 or time-of-flight of a projectile from gun 11 to target 12.

In the drawing (Fig. 5) the cathode ray tube gun sight is designated generally by the numeral 15 and includes a cathode ray tube 63, mounted in a cylindrical housing 21 by means of suitable positioning elements 22 and 23. The conductors leading to the cathode ray tube from terminals

90, 100, 90' and 100' (Fig. 9) are contained in an insulated cable 24. The cylindrical housing 21 is attached by screws or other suitable means to the lower end of the main housing 25 which has an opening 26 at the point of attachment. A plane reflecting mirror 27 is located in the lower end of the housing 25 at an angle of approximately 45° to the horizontal. Pivoted to the upper end of the housing 25 is a semi-reflecting flat glass plate 28, which is inclined at an angle of approximately 45° to the horizontal and which may be lifted upwardly on a pivot for purposes of cleaning the inside of housing 25. A suitable catch 29 is provided for holding the glass 28 in position. In the upper end of the rear wall of housing 25 is an opening 30 which provides communication between the interior of housing 25 and the interior of the eye piece support 31, which is attached to the housing by means of screws or other suitable means. A rubber eye piece 32 and a peep 33 are mounted on a tube 34 which is slidably mounted in the outer end of the support 31. The position of tube 34 in the support 31 is adjusted by means of a spring pressed plunger 35 which cooperates with notches 36 on the tube. A knob 37 attached to the tube serves as a means for moving the tube. A mounting bracket 38 is attached to the lower front wall of the housing 25 to provide means for mounting the unit on a gun.

In order to boresight this unit, mirror 27 is pivotally attached to the side walls of the housing 25 and a mechanism consisting of two screws 41 and 42, mounted on the outside of the housing 25 is provided. The screws 41 and 42 are tightened against an arm 45 which turns with the mirror, and by varying the relative positions of the screws 41 and 42 the mirror 27 may be positioned accurately to boresight the gun in elevation. For boresighting in train, the sight is rotated on its supporting member 46 (Fig. 8) which fits into bracket 38. A screw (not shown) or other device for positioning the sight correctly in train may be provided.

The unit shown in Fig. 6 is somewhat similar to that illustrated in Fig. 5, but instead of providing a mirror such as that shown at 27 in Fig. 3, the cathode ray tube 63 is mounted in a vertical position and a collimating lens system is provided above the cathode ray tube at 47 to constitute a collimated sight.

The cathode ray tube employed in the sight is of any conventional type having suitable electron gun structural elements for projecting an electron beam from its cathode onto a fluorescent screen 50. A deflecting means comprising vertical (106, 107) and horizontal (96, 95) pairs of electrostatic deflecting plates is provided in the tube for deflecting the electron beam as is common practice in the cathode ray tube art.

In the cathode ray tube of the sight shown in Fig. 5, a mark such as a spot or circle is formed on the screen 50 and is reflected upwardly by mirror 27 and rearwardly by the flat piece of glass 28 to the eye of the gunner positioned behind the rubber eye piece 32. The gunner looking into the sight through the rubber eye piece sees the image of the spot or circle created by the cathode ray tube and reflected by the optical elements 27, 28 into the sight line and at the same time views the target through this piece of glass 28. The gun is aimed by centering or effectively superimposing the reflected image on the target. By means of the electrical controls for the cathode ray tube, hereinbelow described, the mark

on the tube screen is able to provide various corrections. Movement of the mark on the screen 50 produces a corresponding movement of the image reflected into the gunner's line of sight by the optical elements 27, 28 so that a new line of sight is established to enable the gunner to adjust the position of the gun to correspond to the sighting corrections put into the cathode ray tube.

Due to the fact that the line of sight is defined by the image reflected by the optical elements 27, 28 into the operator's field of view and the peep 33 located in the rubber eye piece, the amount of correction of the line of sight by a given movement of the image depends upon the position of the peep in the eye piece with relation to mirror 28. The rubber eye piece and peep are shown adjustable so that this correction can be calibrated by movement of the eye piece and peep in and out of the support 31.

The collimated type of sight shown in Fig. 6 possesses the advantage that the eye of the gunner need not be in a fixed position relative to the peep as is necessary in the unit shown in Fig. 5. In the Fig. 6 embodiment the mark created on the screen 50 of the cathode ray tube is collimated as in an illuminated sight by means of the lens system 47 (or 48) and focused an infinite distance away. The mark is reflected by the glass plate 28 into the gunner's field of view. The device shown in Fig. 6 may be boresighted by adjustment of the bracket 38 and by a simple adjustment of the angle of the semireflecting plate 28.

It will be noted that the optical elements 27 and 28 are normally stationary with respect to the cathode ray tube means 17. The mirrors do not normally move as in the Mark 14 sight nor is the reference image mechanically reflected as in the Alkan sight.

In attaching the cathode ray tube sight to a gun, the sight is conventionally placed as near the trunnions of the gun as possible so that the eye of the gunner may remain at approximately the same height for all angles of elevation of the gun. In Fig. 3, the cathode ray unit of the type shown in Fig. 5 is shown mounted on an anti-aircraft machine gun, and in Fig. 4 a gunner is shown with the sight in operation (only the hands and an eye of the gunner being shown).

The sighting arrangement also includes means actuated by rotative movements of the gun for controlling the positioning means included in the cathode ray tube. This electrical means so responsive to dynamic movements of the gun and elevation and in azimuth for displacing the reference mark in elevation and in azimuth by an amount which is functionally related to the rates of such gun movement, comprises a voltage generator 39 and a voltage generator 44. Generator 39 is mounted on the carriage yoke 52 of the gun mount and is adapted to be actuated by a gear 53 which meshes with a beveled gear segment 54 mounted on the gun carriage. Elevation or depression of the gun causes rotation of the rotor of generator 39, the voltage generated being directly proportional to the rate at which the gun is elevated or depressed. The output voltage of this generator is applied to a vertical deflection amplifier and gain (range) control unit 70 68' (Fig. 9). Another voltage generator 44 is mounted on the carriage yoke and has on its rotor a pinion gear 55 which meshes with a ring gear 56 mounted on the stand 57 on which the gun is supported. When the gun is trained, the rotor of generator 44 is rotated, due to the en-

gagement of pinion gear 55 with ring gear 56, and a voltage proportional to the rate of train is generated and applied to a horizontal deflection amplifier and gain (range) control 68 (Fig. 9). Generators 39 and 44 are of the direct current type and are wound so that the polarity of the voltage generated is reversed when the direction of rotation is reversed and so that the voltage generated varies with the speed of rotation.

By means of the rate generators 39 and 44 just described, two separate output voltages are developed and individually put into the amplifying units 68' and 68 as the gun is moved in following a target, the value of each voltage being directly proportional to the rates of elevation and train, respectively, of the gun. These voltages are functionally related to the vertical and horizontal components of the velocity of the target. These voltages are applied to the amplifiers, there amplified and then applied to the cathode ray tube 63 to control the location of the mark on the screen 50 and thus to define the line of sight and to control the direction of fire of the gun.

When the sight is used as a rate sight, utilizing the rate generators 39 and 44, it is essential that the voltages applied to the amplifier be varied in accordance with range or time of flight. This is extremely important due to the fact that the angular rate of movement of the gun in following a target traveling at a given linear velocity with respect to the gun varies inversely as the range. Assuming that the projectile velocity remains constant for all ranges for any given target speed relative to the gun, the lead angle remains constant for all ranges. In order to prevent the increased angular rate of movement of the gun for a near target from deflecting the reference mark excessively and giving too large a lead angle, the amount of deflection of the mark for a given rate of angular movement of the gun must be decreased as the range decreases. This change in the amount of deflection of the mark is accomplished by means of elements 73-74 and 73'-74' in units 68 and 68', respectively (Fig. 9). Range settings are put into the amplifier by manual adjustment of a range setting control comprising ganged sliding contacts 74 and 74'.

Although it was assumed in the preceding paragraph that the projectile velocity remains constant for all ranges, this is, of course, not entirely true. Decreasing projectile velocity with increased range is a factor which should be considered in a rate sight. As the range increases, the average velocity of the projectile decreases and the lead angle must be increased slightly with increased range to compensate for this loss of projectile velocity. This correction is sometimes called a "time of flight" correction and should be considered in the range setting device just discussed. As is obvious to those skilled in the art, this is accomplished by appropriate shaping of resistor 73 and 73', as suggested at lines 108 to 111, page 2, of United States Patent No. 1,322,153, issued to J. S. Wilson and W. E. Dalby, on November 18, 1919. Thus the final correction made in the position of the reference image in the sight by the adjustment of the range control 65, 74, 74' is functionally related to time of flight, which, as indicated, does not vary precisely linearly with the range.

The sighting arrangement also includes a superelevation potentiometer 18 (Fig. 8). There

have already been described arrangements for so disturbing the line of sight as to introduce corrections for target velocity and range. However, the solution of the problem posed in Fig. 2 requires a superelevation control for applying to the disturbing means (deflecting plates 106 and 107, Fig. 9), through the amplifying unit 68, an electrical signal having a magnitude trigonometrically functionally related to the angle of elevation of the gun, thereby to cause the electrostatic plates 106 and 107 to disturb the reference mark and the line of sight by an amount trigonometrically functionally related (as the cosine) to the angle of elevation. When such a superelevation control is provided, the maintenance of the line of sight on a target causes the line of fire to be angularly elevated with respect to the line of sight by the amount of the desired superelevation correction. The means for supplying the superelevation correction comprises a potentiometer 18. The electrical details of the potentiometer 18 are shown in Fig. 9 and its operation is hereinbelow described. It sliding contact 66 (Fig. 9) is positioned by a linkage 59 secured to the carriage yoke 52. The housing portion 58 of the potentiometer contains the resistor 67 (Fig. 9) and is secured to the gun, so that it moves in elevation with the gun. Movement of the gun in elevation causes movement of the linkage 59 and appropriate movement (hereinbelow described) of sliding contact 66 in potentiometer 18. Potentiometer 18 and linkage 59 are so arranged that when the gun is on the true horizontal, sliding contact 66 (Fig. 9) is adjacent to terminal 65 and the full voltage output of battery 62 is applied to resistor 64. On the other hand, when the gun is pointed in a vertical direction, contact 66 is effectively connected to the negative terminal of battery 62 and no voltage is applied from the output of potentiometer 18 to resistor 64. Between these two limits, the voltage applied to resistor 64 by battery 62 and potentiometer 18 varies as the cosine of the angle of elevation or depression of the gun and resistor 67 is appropriately shaped to accomplish this objective in a manner indicated in my copending U. S. patent application Serial No. 636,045, filed December 19, 1945, and entitled "Gun sight superelevation control device."

The output signal from potentiometer 18 and the output signal of generator 39 cooperate to cause the vertical position of the reference image to be determined by superelevation as well as by the elevational component of the velocity of the target and range. The elevational position of the reference image is a function of two arguments, the first of these being a rate or dynamic condition and the second being a position or static condition. Since the superelevation correction is also functionally related to range, the sum of the outputs of generator 39 and potentiometer 18 is applied to gain control 73', 74' of unit 68'.

Referring now specifically to Fig. 9, there is illustrated a complete electrical system for so coupling the train generator 44 and the combination of the elevation generator 39 and the superelevation control potentiometer 18 to the horizontal plates and the vertical beam-deflecting plates, respectively, of the cathode ray tube 63 as to cause the reticle provided by the spot on the cathode ray tube screen to be positioned in coordination with the movements of the gun in train and in elevation. This system comprises the cathode ray tube 63, a horizontal deflection amplifier and gain (range) control 68 and its as-

sociated input coupling circuit to the train generator and output coupling circuit to the horizontal beam-deflecting plates of the cathode ray tube, a vertical deflection amplifier and gain (range) control 68' and its associated input coupling circuit to the combination of the elevation generator 39 and the superelevation control potentiometer 18 as well as its associated output coupling circuit to the vertical beam-deflecting plates of the cathode ray tube, and a conventional power supply 69.

Units 68 and 68' are identical in construction and in operation, so that the following detailed description is confined to unit 68, and unit 68' is shown primarily in block form, only a few elements being detailed. All elements of unit 68' shown in detail in Fig. 9 bear the same reference numerals as the corresponding elements of unit 68, with the addition of a prime mark for purposes of facilitating the description thereof. The system comprising unit 68, unit 68', power supply 69 and cathode-ray tube 63 is of the prior art, and the circuits included in those units have been copied from pages 16 and 17 of the unclassified operating instructions book for the Du Mont type 208 cathode-ray oscilloscope equipment, published in 1943 by the Allen B. Du Mont Laboratories, Incorporated, Passaic, New Jersey, U. S. A.; this publication being fully identified as DE-246, issue 3. D. C. operation is described at pages 12 and 24 of that book. The circuit is well known to those skilled in the electrical art and is included herein for the sole purpose of insuring against any doubts that it may not be equally well known to those skilled in the gun sight art. It is also shown at page 225 of the book "Ultra-High Frequency Techniques," by Brainerd, Koehler, Reich and Woodruff, published in 1942 by D. Van Nostrand Company, Inc., 250 4th Avenue, New York, New York.

The output terminals of the train generator 71, 72 are coupled to a voltage divider 73. This divider with its sliding contact 74 constitutes a potentiometer or gain (range) control in that it provides for a division of the output signal of the train generator and a choice of the portion of that signal applied to the remaining elements of unit 68 in cascade with this potentiometer. The coupling between the elevation generator and unit 68' is generally similar to the coupling between the train generator and unit 68, appropriate modifications being made because of the fact that unit 68' is controlled both by elevation-lead-angle-correction voltages and superelevation correction voltages. To this end, the output terminals 71', 72' of the elevation generator are connected in series with a resistor 64, and the series combination of resistor 64 and the output circuit of generator 39 is coupled to the resistor portion 73' of a potentiometer comprising resistor 73' and sliding contact 74'. The last mentioned sliding contact provides gain (range) control. The sliding contacts 74 and 74' are ganged by any suitable expedient indicated by the dashed line 65 in order that the range correction may be simultaneously introduced for both elevation and train signal channels. The voltage across resistor 73' is equal to the sum of the voltage generated by the elevation generator 39 and that appearing in resistor 64. The last-mentioned voltage is equal to the drop between center tap terminal 65 and the sliding contact 66 of the superelevation control potentiometer. This potentiometer includes a resistor 67 having a center tap coupled to one terminal of a battery 62 and

75 having both of its leads coupled to the other terminal of that battery. The terminals of resistor 64 are individually coupled to sliding contact 66 and the junction of the leads of resistor 67 and the battery 62.

The output voltage of the train generator appearing across resistor 73 is functionally related to the rate of tracking of the target in train or to the horizontal component of target velocity. 10 The signal is also functionally related to range or time-of-flight by reason of the setting of sliding contact 74. Similarly, the signal appearing across resistor 73' is a composite of the signal appearing across resistor 64, this signal being functionally related to the elevational position of the gun with respect to the horizontal (superelevation correction) and the signal output of the elevation generator, the last named signal being functionally related to the rate of tracking of the target in elevation or the vertical component of target velocity. This composite signal is functionally related to range by reason of the adjustment of sliding contact 74'.

The general operation of unit 68 is such as to 25 amplify the signal appearing across resistor 73 to such an extent as to permit that signal to govern the horizontal deflection of the beam of cathode ray tube 63. Similarly the function of unit 68' is to amplify the signal appearing across resistor 73' to such a degree as to permit it to control the vertical deflection of the beam.

Referring now specifically to the signaling circuit of unit 68, the signal appearing between sliding contact 74 and ground is applied to the control electrode of a triode tube 75 (1/2 6F8G.) Coupled to this control electrode is a grid resistor 76 (one megohm). The cathode is connected to a terminal 79 (at minus 280 volts with respect to ground) through a series combination of resistors 77 and 78 (15,000 ohms potentiometer and 300,000 ohms, respectively). The anode of this tube is coupled to the positive terminal 80 of an appropriate source of space current herein below described (at a potential of plus 155 volts). 35 Tube 75 is arranged as a cathode follower circuit and its output circuit is coupled to the input circuit of tube 81, the control electrode of the latter being connected to a sliding contact 98 on resistor 77. Tubes 81 and 82 (each 6V6) are arranged as a paraphrase amplifier and use phase inversion for the purpose of converting the output signal of tube 75 (which is relatively weak and unbalanced to ground) to a relatively high voltage signal, balanced with respect to ground 40 and applied to the horizontal beam deflecting elements of tube 63 in such a manner as to minimize undesired defocusing. To this end the cathodes of tube 81 and tube 82 are connected, their common terminal 84 is connected to ground and applied to the horizontal beam deflecting elements of tube 63 in such a manner as to minimize undesired defocusing. To this end the cathodes of tube 81 and tube 82 are connected, their common terminal 84 is connected to ground 45 through a resistor 83 (400 ohms) and the control electrode of tube 82 is grounded. The output signal from tube 75 is employed to drive tube 81 and this signal is of such a polarity as to be a degenerative signal with respect to tube 82. The input circuits of tubes 81 and 82 are so proportioned that the voltage effective between grid and cathode of tube 82 is approximately half of the input voltage applied to the combination of tubes 81 and 82 from tube 75. Similarly, the voltage effective between grid and cathode of tube 81 is also approximately half of that input voltage. Thus the input voltages of tubes 81 and 82 are substantially equal but are of opposite polarity when referred to their control electrodes, 50 so that the output signals are of approximately 55 60 65 70 75

the same amplitude but of opposite polarity. The anodes of these tubes are coupled to a terminal 89 (plus 280 volts) through two series combinations individually comprising resistor 85 and choke 87 (25,000 ohms and 7-19 millihenries, respectively) and resistor 86 and choke 88 (25,000 ohms and 719 millihenries, respectively). Screen potential is supplied from terminal 89 to the screen grids of these two tubes 81 and 82 by connecting the junction of these screen grids through a resistor 90 (150,000 ohms) to terminal 89. The anodes of the tubes 81 and 82 are individually coupled through individual parallel combinations of resistor 91 and condenser 92 (750,000 ohms and 0.25 microfarad, respectively) and resistor 93 and condenser 94 (750,000 ohms and 0.25 microfarad, respectively) to the horizontal beam deflecting plate 95 and 96 of tube 63.

As is well known to those skilled in the art the general operation of and cooperation between units 68 and 63 is such that when the signal appearing in resistor 73 becomes more positive with respect to ground, plate 95 becomes more negative and plate 96 becomes more positive, with the result that the spot provided by the electron beam of tube 63 is moved to the right. Similarly, when the signal appearing across resistor 73 is of negative polarity with respect to ground the spot is deflected toward plate 95. The average direct current voltages of the plates of tubes 81 and 82 act as electron beam-positioning voltages, since there are no blocking capacitors to keep these potentials off the deflecting plates 95 and 96.

The sliding contact 98 on resistor 77 acts as a positioning control or spotting control. When this sliding contact is moved upwardly toward the cathode of tube 75, it will be assumed that the potential of the grid of tube 81 is given a positive increment. This increment is amplified and shifted in phase by 180 degrees by tube 81, appearing at its plate as a change in potential equal to the amplification of the stage multiplied by the original increment. In this manner the potential of the deflection plate 95 becomes more negative and repels the electron beam. At the same time a positive amplified change in potential appears at the plate of tube 82, thus making the cathode ray tube deflection plate 96 more positive by that amount and that plate attracts the electron beam toward it. The average potential of the space between the deflection plates has been maintained constant, but the fluorescent spot has assumed a new position on the cathode ray tube screen. Signal potentials from the train generator are then superimposed upon the steady positioning potential to deflect the spot with reference to the base position so established. When the polarity of the signal applied to resistor 73 is reversed, the direction of deflection is also reversed.

The cathode follower 75 is so designed that there is a point about the middle of the potentiometer comprising resistor 77 at which the voltage to ground is zero. This is practicable because the anode of that tube is connected to terminal 80 and the cathode is connected through a set of load resistors to terminal 79. When the position-control sliding contact 98 is set at the ground potential point, the bias on tube 81 must be the same as the bias on tube 82. If no signal is applied, both of those tubes conduct the same amount of current and the voltage at the plate of tube 81 is the same as the voltage at the plate of tube 82. The spot will then be in the center 75 tube 63.

of the screen if the electron gun of tube 63 is properly aimed.

If it is desired to move the spot in one direction in order to establish a reference position about which the output signals of the train generator produce variations, the sliding contact on resistor 77 is moved upwardly, say, so that the grid of tube 81 becomes more positive with respect to ground. This causes tube 81 to have a larger average current and the cathodes of tubes 81 and 82 tend to become more positive. However, when the cathode of tube 82 becomes more positive, the bias on this tube is increased and it passes a smaller current. This tends to reduce the voltage drop across the common cathode resistor 83, but the result is that the voltage across resistor 83 will be larger than it was when the grid of tube 81 was at ground potential. Therefore, since tube 81 is passing a larger current than before, and tube 82 in passing a smaller current, the average voltage at the plate of tube 82 will be more positive than the voltage at the plate of tube 81, and the spot is attracted at the right toward deflecting plate 96. In a similar way, it is obvious that the spot will move to the left or toward deflecting plate 95, if the position control 98 is so moved as to make the grid of tube 81 more negative with respect to ground. Movement of the position control 98 has very little effect on the gain of tubes 81 and 82, since the actual shift of bias is so small that the tubes still work on the linear portions of their characteristics. The overall gain is slightly affected because the amplitude of the input signal to tube 81 varies somewhat as the sliding contact 98 on resistor 77 is moved. However, since resistor 78 is large compared to resistor 77, most of the signal voltage is developed across resistor 78. Thus the overall gain is decreased or increased approximately one per cent. Since the voltage change which appears across resistors 91 and 93 when the position control 98 is moved, is only about 10 per cent of the change in voltage at the plates of tubes 81 and 82, capacitors 92 and 93 can change their charge so rapidly that the lag between the adjustment of control 98 and the assumption of a new position by the spot on the cathode ray tube is not noticeable.

In my co-pending U. S. Patent application, Serial Number 627,515, filed in the U. S. Patent Office on November 8, 1945, and entitled "Electrical control device," there is shown a novel combination of two potentiometers for centering control of a cathode ray tube beam. One of these potentiometers may be used as resistor 77 and position control 98 in unit 68, and the other of these potentiometers can be used as resistor 77' and position control 98' (not shown) included in unit 68.

The power supply 69 furnishes biasing and the tube filament-heating potentials for units 68, 68', and 63. It comprises a conventional power transformer 110, which has a primary winding 111, coupled through terminals 112 and 113 to a suitable 115 volt, 60 cycle, alternating current source (not shown). The transformer has a secondary winding 114 (6.3 volts) for supplying filament-heating current to the cathode ray tube, as indicated by the letters Z-Z, and a secondary winding 115 (6.3 volts) for furnishing filament-heating current to tubes 75, 81 and 82 as indicated by the letters X-X.

In order to provide a potential of 280 volts above ground, which potential is applied to terminals 89 and 89' and to the intensifier electrode 117 of tube 63, there is provided a rectifier circuit com-

prising a center-tapped secondary winding portion 118 in transformer 110 and a full wave rectifier tube 119 (type 80). The center tap is grounded and it comprises the negative terminal of this 280 volt source. The plates are connected to the terminals of this secondary portion 118 and the filament of tube 119 is energized from a center-tapped secondary winding 120 (5 volts). The center tap of winding 120 constitutes the positive terminal of this voltage source. In order to filter this voltage the center tap of winding 120 is brought out to terminal 123 through a filter network comprising shunt condensers 124, 125 and 126 (40 microfarads, 16 microfarads, and 1 microfarad respectively) and series chokes 128 and 129 (each 8 henries).

In order to provide a 155 volt regulated potential for application to terminals 80 and 80', terminal 123, at which a potential of 280 volts (positive with respect to ground) is available, is connected to ground through a series combination comprising the anode-cathode path of a tube 130 (6V6) and resistors 131 and 132 (each 500,000 ohms). In order to provide a negative bias for the control electrode of tube 130 that electrode is connected to the junction of resistor 134 (500,000 ohms) and the anode of a tube 135. A potential of plus 155 volts is made available at terminal 136 (i. e. the junction of resistors 134 and 131). Terminal 136 is connected to terminal 80 and 80' of unit 68 and 68'. In order to stabilize this 155 volt potential there is provided a conventional voltage regulator comprising a pentode tube 135 (6SJ7) and a neon tube 137 (1/4 watt). The anode-cathode paths of these tubes are connected in series between terminal 136 and ground. The screen grid of tube 135 is connected to terminal 136. The control electrode biasing potential applied to tube 135 is adjusted by positioning a sliding contact 140 on resistor 132, this sliding contact being connected to the control electrode of tube 135. Condensers 141 and 142 (each 1 microfarad) are connected respectively, between terminal 138 and the control electrode of tube 135 and between terminal 136 and ground.

A very stable voltage regulator is thus provided by taking advantage of the high amplification of the pentode vacuum tube 135. This voltage regulator produces an output of voltage which is independent of fluctuations in the alternating current supply and changes in load over a wide range. The output voltage of this regulator is developed across the resistors 131 and 132 in parallel with the resistance of the load. These resistors make up the resistance of one part of a total voltage divider. The other resistance, through which all of the load current must flow, is the plate to cathode resistance of tube 130. The other elements of the circuit are used to control the resistance of tube 130 and therefore, to maintain a constant voltage across the load. The voltage at terminal 136 is the regulated voltage output of the regulator. The potential of the cathode of tube 135 is held at a constant positive value by the neon tube 137. The control grid potential of tube 135 is a voltage selected by the potentiometer comprising resistor 132 and sliding contact 140. This potentiometer is set so that the grid voltage is less positive than the cathode by an amount (the bias) which causes tube 135 to pass a certain plate current. This plate current flows through the plate load resistance 134 and causes a drop across it. The magnitude of the voltage across resistor 134 is the bias on tube 130. Therefore the adjustment of the potentiometer setting 140 establishes the

normal resistance of tube 130. This adjustment is used to set the value of load voltage which the regulator is to maintain.

If the load voltage tends to rise, whether from a decrease in the load current or from an increase in the input voltage, the voltage on the grid of tube 135 also tends to rise (become less negative), the cathode voltage remaining practically constant. Tube 135 then conducts more current, because the bias is smaller. A greater current flows through resistor 134 which causes a greater voltage drop across this resistor. This voltage, which is the bias voltage for tube 130, causes the plate resistance of tube 130 to increase. A larger portion of the available voltage appears across the higher resistance of tube 130 and the load voltage remains practically constant. The action is reversed as the load voltage tends to fall. The anode of the glow tube 137 is connected to the cathode of tube 135 and to the regulator voltage output terminal 136 through resistor 138 (100,000 ohms). It is necessary to connect the glow tube to the high potential terminal 136 in this manner in order to cause the gas in this tube to ionize when the power supply is first turned on. All of the load current must pass through tube 130. For this reason this tube must be capable of passing a large current. Addition of the condenser 141 increases the fraction of the voltage change impressed upon the grid of tube 135 when the change occurs rapidly. If the reactance of this condenser at ripple frequency is small in comparison with the resistance which it shunts, the condenser appreciably increases the ability of the circuit to reduce the ripple.

Voltage regulators of this general type are fully described in "The Theory and Applications of Electron Tubes," by Herbert J. Reich, second edition, McGraw Hill Book Company, New York, 1944, section 14-13, pages 590 to 594, and in the publication "Radio Engineer's Handbook," by Frederick E. Terman, first edition, McGraw Hill Book Company, New York, 1943, section 8, paragraph 9, pages 614 to 617.

It is also necessary to make available for application to terminals 79 and 79' a potential of minus 280 volts with respect to ground. The leads of secondary winding 115 of the power transformer are connected to the filaments of a full wave rectifier tube 144 (6X5GTG). The ground terminal of winding 118 constitutes the positive terminal of this potential source and the junction of the cathodes of tube 144 is connected to one lead of winding 118. For filtering purposes there is provided a combination of series resistor 145 (47,000 ohms) and shunt condensers 146 and 148 (1 microfarad and 16 microfarads, respectively). The terminal of resistor 145 remote from tube 144 is brought out to an output terminal 149 and that terminal is connected to terminals 79 and 79' of units 68 and 68' respectively.

Filament potentials (5 volts) for tubes 130 and 135 are provided by a secondary winding 151 on transformer 110 as indicated by the letters Y-Y.

There remains to be described the high potential source for the anodes of the cathode ray tube 63. As is conventional in tubes of this type the second or accelerating anode 153 is grounded so that it is necessary to bias the cathode 154 negatively with respect to ground so that the anodes are effectively biased positively with respect to the cathode. Therefore, there is provided a high potential rectifier comprising that portion of winding 118 between grounded terminal 156 and lead 158 and a rectifier tube 159 (type 80), the plates of this tube being connected together and its fila-

ment being energized from portion 160 of that winding. The junction of the plates constitutes the negative lead of this potential source (minus 1,100 volts) and this junction is brought out through resistor 164 to terminal 162. Filtering is provided by a shunt condenser 163 (0.5 microfarad) and a series resistor 164 (50,000 ohms) so that there is available at terminal 162 a potential of approximately minus 1,050 volts. Terminal 162 is also connected to terminal 105 and 105' of units 68 and 68', respectively.

All of the potential sources for units 68 and 68' have now been described and there remains to be described the arrangement by which the electron-gun electrodes of the cathode ray tube are excited. There is arranged between terminal 162 and ground a conventional bleeder resistor comprising four individual resistors 166, 167, 168, and 169 (100,000 ohms potentiometer, 200,000 ohms, 500,000 ohms potentiometer, and 1 meg-ohm, respectively). The cathode is connected to potentiometer 166 by a sliding contact 170 which serves as a spot intensity control. The brilliancy control electrode 171 is coupled to terminal 162, filtering being provided by a combination of shunt condenser 172 (0.1 microfarad) and a series resistor 173 (100,000 ohms). Movement of sliding contact 170 varies the positive bias of cathode 154 with respect to the brilliancy control electrode 171 and therefore varies the intensity of the spot on the tube screen. The focusing anode 175 is positively biased with respect to the cathode by connection through a sliding contact 176 to potentiometer 168. Contact 176 serves as a focusing control. Since the accelerating anode 153 is grounded it is effectively connected to the ground terminal of resistor 169 and is therefore highly positively biased with respect to the cathode. The intensifier electrode 117 is coupled to the plus 280 volt terminal 123 and is therefore still more highly positively biased with respect to the cathode.

It is desirable that the junction of terminal 99 and resistors 93 and 103 be at a lower potential than plus 280 volts. It is also desirable that the junction of terminal 100 and resistors 91 and 101 be at a lower potential than plus 280 volts. These desirable conditions should exist when no signal outputs are being taken from train generator 44 and elevation generator 39. Accordingly the minus 1050 volt terminal 105 is connected to the junction of the resistors 102 and 104. In passing from terminal 105 to terminal 89 through resistor 104, resistor 103, resistor 93, resistor 86, and choke 88, the potential increases from minus 1050 volts to 280 volts. Similarly, in passing from terminal 105 to terminal 89 through elements 102, 101, 91, 85 and 87 a similar increase in potential is provided. Thus the two above-mentioned objectives are accomplished.

A cathode ray tube having an electron gun structure and post-deflection acceleration means is fully described on page 342 of the above-mentioned publication by Terman and is old in the cathode ray tube art.

The operation of the circuit disclosed in Fig. 9 is well known to those skilled in the cathode ray tube art and a detailed description thereof is not necessary. Briefly, however, it will be assumed under a particular condition that the train generator output signal is of positive polarity. The ultimate effect of this signal on the position of the spot between plates 95 and 96 is considered. This signal is applied to the input circuit of tube

15. The cathode of tube 75 follows the grid potential and sliding contact 98, under the assumed condition, becomes more positive with respect to ground so that a signal of positive polarity is applied to tube 81. This signal is of negative polarity as applied to tube 82. Tubes 81 and 82 shift the applied signal in phase by 180° so that the plate of 81 becomes more negative and that of 82 more positive. The result is that terminal 100 and beam deflecting plate 95 become more negative and repel the cathode ray tube beam, while terminal 99 and deflecting plate 96 become more positive and attract the cathode ray tube beam. The spot provided by the beam is therefore deflected or moved to the right. This is the case when the gunner is tracking a target which has a velocity component toward the left. The amount of the deflection is functionally related to target velocity, since it is functionally related to the magnitude of the output signal of the train generator. Additionally, the beam displacement is related to range, since it is determined in part by the setting of gain control 74. Thus the positions of the spot and the reticle it provides are determined in accordance with the ballistic corrections required. As range increases the sliding contact 74 on the gain control should be moved away from ground. For purposes of spotting corrections the position control 98 is employed.

30 The operation of unit 68' and plates 106 and 107 is precisely the same as that of unit 68 and its associated beam deflecting plates. However, the input signal applied to unit 68 is functionally related to the sum of the output voltage of the 35 elevation generator and the output voltage of the superelevation control potentiometer, the aggregate of those voltages being functionally related to range by reason of the operation of gain control 74'. The spot is deflected up or down in accordance with the rate of ascent or descent of a target.

In Fig. 10 there is illustrated an arrangement for providing a circular reticle rather than a reticle in the form of a spot. This arrangement is of the prior art and most of its components are found in the following publications: "Cathode Ray Tubes and Allied Types," Technical Series TS-2, RCA Mfg. Co., Inc., Harrison, N. J., 1935, pages 78 to 85 inclusive; "The Radio Amateur's Handbook," 20th edition, 1943, published by the American Radio Relay League, West Hartford, Conn., pages 52 to 55, inclusive, and pages 396 to 398 inclusive; the above mentioned publication by Reich, pages 628 to 634, inclusive, particularly page 634, and the above-mentioned publication by Terman, pages 947 to 950, inclusive, particularly page 948. This arrangement is generally similar to that disclosed in Fig. 10 and includes train and elevation generators, a superelevation control potentiometer, and suitable direct current amplifiers 180 and 181. Since the electrostatic beam-deflecting plates 96 and 106 are here grounded, amplifiers 180 and 181 are so designed so as to produce amplified output signals unbalanced to ground. Amplifier 180 is coupled to plates 95 and 96 and amplifier 181 is coupled to plates 106 and 107. The amplifiers may include any conventional gain control to provide for range adjustment. Inserted between amplifier 180 and plate 95 is a resistor 182. Similarly arranged between plate 107 and amplifier 181 is a resistor 183. Time-quadrature alternating current voltages are individually impressed upon these resistors from the separate phases 184 and 75 185 of a two-phase alternating current generator

17

186. The time-quadrature voltages from generator 186 cause the beam to sweep in a circular pattern and thus to provide a circular reticle. The size of this reticle can be determined by varying the output voltages of generator 186, in various obvious manners well known to those skilled in the art. For example, the resistors can be employed as potentiometers and their sliding contacts are ganged by any suitable expedient indicated by the dashed line 181. The signals representative of ballistic corrections then displace the circular reticle rather than the spot type of reticle provided by the Fig. 9 circuit. The operation of the Fig. 10 system is otherwise generally similar to that of the Fig. 9 system.

While there have been shown and described what are at present considered to be the preferred embodiments of the present invention it will be obvious to those skilled in the art that various changes and modifications may be made therein without departing from the true scope of the invention, and it is, accordingly, intended in the appended claims to cover all such changes and modifications as fall within the true scope of the invention and outside of the proper scope of the prior art.

The invention herein described may be manufactured and used by or for the Government of the United States of America for governmental purposes without the payment of any royalties thereon or therefor.

I claim:

1. An automatic compensating gunsight for establishing the line of fire of a gun comprising; a cathode ray tube for providing a reference mark, optical means for imposing an image of said mark in the line of sight of a gunner whereby the image may be viewed simultaneously with a target, means responsive to movement of the sight in the plane of train for providing an electrical signal proportional to the rate of movement of the gunsight in train, means responsive to movement of the sight in the plane of elevation to provide an electrical signal proportional to the rate of movement of the gunsight in elevation, means for amplifying said electrical signals, means for applying the amplified signals to

30

40

45

18

the cathode ray tube for displacing the reference mark upon movement of the gunsight, means for modifying said electrical signals to compensate for changes in the target range, and means linking the gunsight and the gun for movement together in train and in elevation.

2. An automatic compensating gunsight for establishing the line of fire of a gun comprising; a cathode ray tube for providing a reference mark, optical means for imposing an image of said mark in the line of sight of a gunner whereby the image may be viewed simultaneously with a target, means responsive to the movement of the gunsight in the plane of train for providing an electrical signal of a value functionally related to the rate of said movement, means responsive to movement of the gunsight in the plane of elevation for providing an electrical signal functionally related to the rate of said movement, means for changing the value of the signals so obtained, means for applying the changed signals to the elements of the cathode ray tube for displacing the reference mark upon movement of the gunsight, means for modifying said electrical signals to compensate for variations in the target range, and means linking the gunsight and the gun for movement together in train and in elevation.
